UNITED STATES PATENT OFFICE.

LINDSLEY SCHEPMOES, OF HASBROUCK HEIGHTS, NEW JERSEY, ASSIGNOR TO THE SAFETY CAR HEATING & LIGHTING COMPANY, A CORPORATION OF NEW JERSEY.

ELECTRIC FIXTURE.

1,025,208.

Specification of Letters Patent.

Patented May 7, 1912.

Application filed July 31, 1909. Serial No. 510,525.

To all whom it may concern:

Be it known that I, LINDSLEY SCHEPMOES, a citizen of the United States, residing in Hasbrouck Heights, county of Bergen, and 5 State of New Jersey, have invented new and useful Improvements in Electric Fixtures, of which the following is a description.

My invention pertains to that class of 10 electric fixtures, or lamps, adapted to contain an incandescent lamp or bulb and direct the light therefrom in a desired manner and direction, also to protect the lamp or bulb from any injury when situated in exposed 15 places.

My invention has for its particular object 20 to provide a fixture which may be used in railway cars adapted to be secured to the panel alongside one of the seats and to throw its light upon a book or paper which may be held by the occupant of the seat so as to form a reading light.

A further object of my invention is to so direct the light that it will not shine on the occupant of the opposite seat where the 25 occupants face each other as in sleeping cars.

A further object is to provide a lamp or fixture which will direct its light when mounted in a sleeping car as above mentioned in such manner that, when the berth is made down, the light may be used by the occupant of the berth for reading.

My invention is directed particularly to 30 that class of fixtures in which it is desired to use high efficiency bulbs such as the metallic filament bulbs; for example, tantalum or tungsten and on this account it is advantageous that the bulb shall always be held in a vertical position and shall not be subjected to sudden shock or jarring such as is caused by the operation of turning off or on an ordinary key socket.

A further object of my invention is to provide means whereby standard and readily 45 purchasable parts may be used and easily replaced when worn out.

Referring to the drawing Figure I represents a front elevation of my improved fixture. Fig. II shows a vertical section of 50 the parts shown in elevation in Fig. I in a plane at right angles thereto and a section of the panel or wall to which the fixture may be fastened. Also the electric lamp or

bulb and its socket in elevation. Fig. III shows a top plan of that portion of the 55 fixture shown in Figs. I and II which supports the globe and which may be removed from the fixed portion which is attached to the panel or wall. Fig. IV shows a perspective view of that portion of the fixture which 60 is secured to the wall or panel and the means whereby the lamp or bulb socket is carried therein and means whereby a portion of the lamp's rays are directed.

In the drawing, particularly Figs. I and 65 II, 1 represents the back plate which may be fastened to the wall or panel as by the screws 2. This carries the front-plate 3 which may be retained in place as by the screw 4 and which is provided with a prismatic globe 5 70 adapted to direct the light in a desired direction as will hereinafter appear. 6 represents an electric switch carried upon the plate 1 and controlling the current to the lamp or bulb as will readily be seen in Fig. 75 II in which 7 represents an incandescent lamp or bulb carried by the ordinary standard socket 8 and having the usual connection with the switch 6 and the lighting circuit as by means of the wires 9. The socket 80 8 is held in place by the spring-clip 10 which is held in place by the screws 11 engaging the yoke 12 forming part of the back-plate 1 as is clearly shown in Fig. IV. The yoke 12 is provided with an extension 13 carrying 85 the reflector 14, a portion of which is cut away as indicated at 15. The globe 5 is held in place within the member 3 as by means of the flange 16 which engages the flange 17 on the globe, the two flanges being 90 held together as by means of the spun ring 18 which is inserted under two pins, one of which is shown at 19 and then caught under the head of the screw 20, engaging the boss 21 forming part of the member 3 in such 95 manner that, when this screw is drawn up, the spun ring will force the globe 5 tightly into place and allow the same to be readily removed at any time by withdrawal of the screw 20. The member 3 is provided, near 100 the top, with two gibs 22 adapted when held in a certain position to engage the openings 23 in the plate 1 in such manner that, if they be inserted in the said openings and then the member 3 be slightly raised, the 105 gibs 22 will engage the back of the plate 1

so as to firmly hold the member 3 at the top, then making up of the screw 4 into the back-plate as indicated at 24 will hold the member 3 firmly in place.

5 The way in which my lamp or fixture is assembled and made ready for use is as follows, starting with the back-plate and parts assembled as shown in Fig. IV: A socket, as indicated by 8 in Fig. II, is properly 10 wired into the switch 6 and connected through said switch into the lighting circuit. The back-plate 1 may then be screwed in place upon the panel or wall as indicated in Fig. II. The bulb 7 may then 15 be screwed into the socket 8 and the socket pressed into place between the jaws of the spring 10 where it will be firmly held in position. The globe 5 may then be placed in the opening through the flange 16 of the 20 member 3 as shown in Fig. II. Then the spun ring 18 may be caught under the pins 19 and the screw 20 inserted in the boss 21 and drawn up on the ring 18 so as to hold the globe firmly in place. The member 3, 25 with the globe so attached, may then have the members 22 inserted into the openings 23 and then, if the member 3 be raised sufficiently to bring the screw 4 in line with the threaded aperture 25, the gibbs 22 will engage 30 the back of the plate 1 above the slots 23 and if the screw 4 be then made up into the plate 1, the member 3 will be held firmly in place and the lamp will be completely assembled. Then manipulation of the switch 35 as by means of the buttons 26 and 27 will govern the operation of the lamp in a well-known manner. The reflector 14 will cause the rays emitted from the back of the filament to be returned through the lamp and 40 pass outwardly together with the direct rays through the prismatic globe 5, the prisms of which have their angles so selected as to throw the light downwardly at an angle of, approximately, 45 degrees below the horizontal and tend to parallelize the rays in such manner as to cause very slight divergence and in this way prevent the rays from striking the eyes of a person at any appreciable distance to the right or left of the 45 center of the lamp as viewed in Fig. I.

It will be noted that when my lamp is assembled and fixed in its normal position upon a wall or panel a considerable portion thereof is contained in the recess portion 30 of the wall, making a lamp which is always in an operative position without projecting very far into the room or car which is a very valuable feature in lamps designed for lighting car berths. It will also be noticed that 50 with the lamp in place as shown in Fig. II the same may be readily ventilated by a current of air entering the aperture 28 and passing around the bulb 7 and other parts liable to become heated and leaving by aperture 55 29, thus the bulb 7 while entirely covered so

as to be protected, is still so ventilated as to prevent any excess temperature.

I do not wish in any way to limit myself to the exact constructions shown in the drawing for it is obvious that considerable 70 departure can be made in the construction of my improved fixture without departing from the spirit and scope of my invention which is as set forth in the following claims:

75 1. An electric fixture comprising a back-plate, an electric switch carried thereby, an electric socket having a flexible connection with said switch, means carried by the back-plate for supporting said socket, an incandescent lamp carried thereby, combined with a front-plate covering said socket, a light transmitting bowl carried thereby adapted to cover a portion of the incandescent lamp and means whereby the said front plate may 80 be readily attached in a fixed position upon the back-plate.

90 2. An electric fixture comprehending a back-plate, an electric switch carried thereby, an electric socket flexibly connected with 90 said switch and elastic clamping means for supporting said socket carried by said back-plate.

95 3. An electric fixture comprehending a back-plate, an electric switch carried thereby, a pair of flexible jaws carried by said back-plate, a lamp socket held in position by said jaws and flexible connection between the switch and said socket whereby vibration caused by operation of the switch is not 100 transmitted to the said socket.

105 4. An electric fixture comprising a back-plate provided with flexible clamping means for engaging a lamp socket and adapted to hold the same in a vertical position, a lamp carried by said socket and a reflector carried by the back-plate and adapted to reflect the rays of said lamp.

110 5. An electric fixture comprising a portion adapted to be rigidly attached to a vertical wall, an electric lamp supported thereby in a substantially vertical position, combined with a front portion adapted to readily engage the back-plate in a definite operative position and a light transmitting member carried thereby adapted to parallelize the rays emitted from said lamp and cause the same to be emitted in a downward direction.

115 6. An electric fixture comprising a fixed 120 portion, an electric lamp carried thereby adapted to emit rays radially, a reflector carried by said fixed portion adapted to return a portion of the rays through the said lamp, combined with a front member 125 carried by the said fixed member and provided with means for condensing and directing the rays emitted from the lamp and the rays returned therethrough and causing the same to be projected in a downward direc- 130

tion substantially 45 degrees from the horizontal in the form of a cone with little divergence.

7. An electric fixture comprehending a back-plate, means carried thereby for yieldingly supporting an electric lamp, combined with a front-plate adapted to readily engage the said back-plate and cover and protect the lamp supporting means and means carried thereby to direct the lamp's rays in a desired direction.

8. The combination with a wall having a recess, an electric fixture provided with a back-plate and a source of illumination carried thereby and adapted to be partly retained within said recess, of a front-plate carried by said back-plate covering a portion of said recess, and a light transmitting member carried thereby for protecting said source of illumination.

9. An electric fixture comprehending a back-plate, an electric switch carried thereby, an electric socket, flexibly connected with said switch and means carried by the back-plate for supporting said socket in a vertical position and adapted to allow the same to be readily moved into another position for the purpose of inserting a bulb therein.

10. An electric fixture comprehending a back plate, an electric switch carried thereby, an electric lamp socket, flexible holding means for supporting the same carried by said back plate, flexible means for electrically connecting said socket with said switch, and means attached to said back plate for covering and protecting said lamp.

11. An electric fixture comprehending a back plate, an electric switch carried thereby, an electric lamp socket, flexible holding means for supporting the same carried by said back plate, flexible means for electrically connecting said socket with said switch, removable means attached to said back plate for covering said socket and a light transmitting protecting member carried by said last named means.

12. An electric fixture comprehending a back plate, an electric switch carried thereby, an electric lamp socket, flexible holding means for the same carried by said back plate, flexible means for electrically connecting said socket with said switch, readily removable means carried by said back plate for covering and protecting said socket and means carried thereby for directing the ray of said lamp.

13. The combination with a wall having a recess therein, of a perforated plate covering a portion of said recess, an electric socket carried by the said plate and extending into said recess, a reflector carried by said plate and extending into said recess, an electric bulb carried by said socket in operative relation to said reflector whereby said reflector directs a portion of the rays of said bulb

through the perforation in said plate, a member for covering the perforation of said plate, comprehending means for protecting the said bulb and transmitting rays from said bulb therethrough and means for readily attaching said member in operative position upon said plate.

14. The combination with a wall having a recess therein, of a perforated plate covering a portion of said recess, an electric socket carried by the said plate and extending into said recess, a reflector carried by said plate and extending into said recess, an electric bulb carried by said socket in operative relation to said reflector whereby said reflector directs a portion of the rays of said bulb through the perforation in said plate, a member for covering the perforation of said plate, comprehending means for protecting the said bulb and transmitting and directing rays from said bulb.

15. The combination with a wall having a recess therein, of a perforated plate covering a portion of said recess, an electric socket carried by the said plate and extending into said recess, a reflector carried by said plate and extending into said recess, an electric bulb carried by said socket in operative relation to said reflector whereby said reflector directs a portion of the rays of said bulb through the perforation in said plate, a member for covering the perforation of said plate, comprehending means for protecting the said bulb and transmitting the direct rays of said bulb and the rays returned by said reflector therethrough and means for readily attaching said member in operative position upon said plate.

16. The combination with a wall having a recess therein, of a perforated plate covering a portion of said recess, an electric socket carried by the said plate and extending into said recess, a reflector carried by said plate and extending into said recess, an electric bulb carried by said socket in operative relation to said reflector whereby said reflector directs a portion of the rays of said bulb through the perforation in said plate, a member for covering the perforation of said plate comprehending means for protecting the said bulb and directing and transmitting the direct rays of said bulb and the rays returned by said reflector and means for readily attaching said member in operative position upon said plate.

17. The combination with a wall having an opening therein, of a perforated plate attached thereto with the back of said plate against the face of said wall, means for supporting an electric socket carried upon the back of said plate and extending into said opening, a socket, an electric bulb carried by said socket, a reflector extending into said opening and surrounding a portion of said bulb and carried upon the back of said plate

whereby rays from said bulb are returned through the perforation in said plate, a cover portion for the perforation in said plate comprehending a portion for protecting the bulb and transmitting direct rays therefrom and rays from said reflector therethrough and means for holding said mem-

ber in operative position upon the face of said plate.
